CIGARETTE MERCHANTISER

Robert B. Nielsen, Park Ridge, Ill., assignor to Frank Mayer & Associates, Inc., Grafton, Wis.

Original design application Dec. 7, 1970, Ser. No. 26,342, now Patent No. 223,733. Divided and this application
Dec. 17, 1971, Ser. No. 209,509

Term of patent 14 years

Int. Cl. D6—04

U.S. Cl. D6—24

Fig. 1

Fig. 2

FIG. 1 is a perspective view of a cigarette merchandiser showing my new design;

FIG. 2 is a perspective view of the merchandiser with one side in open position;

FIG. 3 is a top plan view on an enlarged scale; and

FIG. 4 is a bottom plan view on an enlarged scale.

This application is a division of Ser. No. D-26,342, filed Dec. 7, 1970, now design Pat. No. D-223,733.

I claim:

The ornamental design for a cigarette merchandiser, as shown and described.
